HYPODERMIC NEEDLE

George E. Barnhart, Pasadena, Calif.

Application July 11, 1936, Serial No. 90,135

8 Claims. (Cl. 128—221)

This invention relates to hypodermic needles.

The general object of the invention is to provide an improved hypodermic needle for injecting anaesthetics as, for example, that used by dental surgeons and by physicians for intravenous injections.

Another object of the invention is to provide an improved depth gauge for use with a hypodermic needle.

10 Another object of the invention is to provide an improved quick injection device for a hypodermic needle.

Another object of the invention is to provide an improved welding device and die for use in 15 making a hypodermic needle.

Another object of the invention is to provide a hypodermic needle which is harder at the tip than at the base and wherein the needle may be made progressively harder from the base to 20 the tip by cold working.

Another object of the invention is to provide a novel hypodermic needle which may depend for its hardness exclusively upon working, with the work preferably a drawing action.

25 Another object of the invention is to provide a hypodermic needle which has greater strength at the base than at the tip and wherein the grain structure is so disposed that maximum strength results may be secured and wherein the greatest strength against lateral bending is 30 secured.

Another object of the invention is to provide a hypodermic needle made of a novel tapered sheet or other blank and wherein preferably the proper thickness is provided in the needle before the latter is formed, thus permitting the sheet or tube to be tapered longitudinally before forming.

Another object of the invention is to provide a 40 needle which varies its outside diameter but which is of uniform strength throughout its length and which has a greater cross section at the base than at the point.

Another object of the invention is to provide a 45 hypodermic needle which is so constructed that the bending strains are gradually transferred into the base.

Another object of the invention is to provide an improved hypodermic needle having a smaller 50 tip than has heretofore been practiced with a normal size base.

Another object of the invention is to provide a hypodermic needle which is drawn to close the seam and is further drawn to cause an elongation of the metal.

Another object of the invention is to provide a tapered needle which may be seamless or which may include an abutting or welded seam wherein the material is hardened due to the working operation.

Other objects and the advantages of the invention will be apparent from the following description taken in connection with the accompanying drawings, wherein:

Fig. 1 is a side elevation of a hypodermic 10 needle and quick injection device embodying the features of my invention;

Fig. 2 is a central, longitudinal view through the needle shown in Fig. 1 with parts broken away;

Fig. 3 is an enlarged, fragmentary, sectional view through the end of the needle;

Fig. 4 is a section taken on line 4—4 of Fig. 2;

Fig. 5 is a section taken on line 5—5 of Fig. 2;

Fig. 6 is a plan view showing one form of blank 20 from which my improved hypodermic needle is made;

Fig. 7 is an enlarged, fragmentary view taken on line 7—7 of Fig. 6;

Fig. 8 is a central, sectional view taken through 25 a modified form of hypodermic needle;

Fig. 9 is a section taken on line 9—9 of Fig. 8;

Fig. 10 is a side elevation showing a modified form of needle and a depth gauge;

Fig. 11 is an enlarged, fragmentary view showing the modified needle and gauge;

Fig. 12 is a side elevation showing a further modified needle;

Fig. 13 is an enlarged, fragmentary, central, sectional view through the needle shown in Fig. 25 12;

Fig. 14 is a section taken on line 14—14 of Fig. 13;

Fig. 15 is a view similar to Fig. 12 showing a further modification;

Fig. 16 is a fragmentary, central, sectional view showing the modified needle of Fig. 15;

Fig. 17 is a view similar to Fig. 16 showing a further modification;

Fig. 18 is a central, sectional view of a further 45 modified needle;

Fig. 19 is an end view showing the manner in which the blank of Fig. 6 is first formed;

Fig. 20 is a fragmentary, side elevation of the blank formed as shown in Fig. 19;

Fig. 21 is a central, sectional view through a forming die;

Fig. 22 is a top plan view of the forming die;

Fig. 23 is an end view, partly in section, showing the welding apparatus;

Fig. 24 is an elevation with parts in section showing the drawing die and associated parts; and

Fig. 25 is an end view showing a modified form 5 of drawing die.

Referring to the drawings by reference characters I have shown my invention as embodied in a hypodermic needle which is indicated generally at 10. As shown this needle is preferably made 10 from a blank 11 shown in Fig. 6 and which blank includes a thickened end portion 12, a bevelled portion 13, and an end portion 14.

In the practice of my invention the blank 11 is 15 preferably formed to the shape shown in Figs. 19 and 20 by forming it over a mandrel, for example, in a brake. The blank formed into the shape shown in Fig. 19 may then be passed through a circular die opening 15 in a taper die element shown at 16 in Fig. 21 or through the 20 die opening 57 shown in Fig. 23. A suitable come-along device 17 may be employed, also a mandrel 18 may be used within the die.

After the edges have been brought to closely 25 abutting relation the formed tube may be passed through a welding apparatus shown in Fig. 24, wherein the device includes a bottom roller 20 which has a tapered groove 21 in its periphery corresponding to the taper of the tube and a pair of top rollers 22 and 23 which are positioned 30 in the opposite side of the seam 24. The rollers 22 and 23 have tapered grooves 25 and 26 therein which correspond to the taper of the tube. The bottom roller 20 is mounted on a shaft 27 which is arranged on a suitable support 28 and has a 35 gear 29 thereon. Above the shaft 27 I arrange another shaft 30 on which a gear 31 is mounted. This gear meshes with the gear 29 previously described. Either the gear 29 or the gear 31 may be suitably driven.

40 The shaft 30 includes a universal 33 which drives the shaft 34 of the roller 23 and the shaft 34 includes another universal 35 which drives the shaft 36 of the roller 22. The shafts 34 and 36 are suitably mounted on supports 37 and 38. The 45 supports 37 and 38 are of metal and are mounted on insulation material 39 and the supports are connected by wires 40 and 41 to a suitable source of electric current so that this current passes to the rollers 22 and 23 which are disposed on opposite sides of the seam thereby producing an 50 electric weld at the seam. The shafts 34 and 36 are suitably insulated from the current.

After the seam is welded or even before it is 55 welded the tube is passed through a forming die 55 such as shown in Fig. 23. This die comprises a plurality of rotatable die elements 46 preferably four in number, some of which are keyed on spindles 47 and others on shafts 48 on a support 49. These die elements are geared through gears 50, 51, 52, and 53 so that they rotate together. The dies are adapted to be driven by a gear 54 60 from a gear 55 which may be driven by a gear 55' from a rack 55" or in any suitable manner.

The dies 46 are provided with peripheral 65 grooves 56 which are similar in shape and of similar 70 taper and the dies are arranged so that they are tangent to each other and their faces meet at an angle of 45° so that the die opening 57 is formed through which the tube is drawn or passed. I now prefer to draw the tube through 75 the die opening by starting the tube with its largest diameter in pressure engagement with the largest portion of the die opening and then rotating the die in advance of the tube as the die advances.

If preferred the die 60 shown in Fig. 25 may be employed where it is desired to produce a bead 61 or a groove 62 in the hypodermic needle, but it will be understood, of course, that a configuration other than that shown in the die 5 mechanism may be employed without departing from the spirit of my invention.

The die shown is of such a shape that it will draw the tube which approximates the general shape shown in Fig. 1 prior to the drawing into 10 the shape shown in Fig. 1. It will be understood, however, that prior to the drawing action the tube may have a shape which differs much from that shown in Fig. 1. In other words the amount of draw will vary with the particular requirements of the hypodermic needle to be manufactured.

After the tube is drawn it is provided with a base member 70 which as shown in Fig. 1 includes a body having a recess 71 in which the end of 20 the needle is fixed and has a reduced cylindrical portion 72 with a collar 73 thereon. The base includes a hollow portion 74 which communicates with the interior of the needle. The forward portion of the needle is bevelled on the 25 line indicated at 75 to sharpen it and may also be provided with plane bevel portions 76 and 77 to provide a novel point to facilitate injection.

The needle shown in Figs. 1 and 2 is also provided with an injection device indicated generally at 80. This device includes a pair of spaced engaging members 81 mounted on opposite sides of the needle. These engaging members are engaged by the reduced end 82 of a coil spring 83 which on its forward end is secured as by soldering to a head 84 having a groove 85 therein which acts in the nature of a suction cup while the head is provided with a pair of rearwardly extending arcuate arms 86 which as shown in Fig. 4 are disposed between the engaging members 81. 40

The arms 86 have a bevelled front end as at 87 and they are of such a size that when the device 84 is moved rearwardly the arms 86 are placed between the members 81 and the bevelled portions 87 and engage under the coil 82 of the 45 spring 83 thus raising this coil above the members 81 whereby the coil is free to move along the needle. The needle is provided with a stop member 87a which is adjustable along the needle, being held in place by a screw 87b. The stop 50 member limits the movement of the arms 86 and thus determines the depth of injection.

In the invention shown in Figs. 1 and 2 the needle includes the thickened portion 87 which is attached to the base 70. The portion 87 is 55 connected to a tapering portion 88 the wall thickness of which tapers. The portion is secured to a cylindrical portion 89 of uniform wall thickness. This cylindrical portion 89 terminates in a beveled portion 90 which is shown as of uniform wall thickness and this portion 90 terminates in a cylindrical portion 91 the end of which is pointed as previously described.

In the operation of my invention the needle 10 is mounted on a suitable syringe and when 60 an injection is to be made the member 85 is placed over the area to be threaded and pressure is applied by moving the syringe and needle 10 towards the member 85. The member 85 moves towards the needle portion 89 until the bevelled 65 face 87 passes beneath the coil 82 lifting the coil 82 from the members 81 whereupon, due to the pressure necessary to compress the spring 83, the needle jumps forward and into the patient so 70 that the desirable quick jabbing action essential

in local anaesthetizing is secured with uniform pressure and piercing and thus with the stop member 87^a employed uniform injection is secured under all usual conditions.

5 In Fig. 8 I show a modification of my invention wherein the head 100 is provided with a needle 101. This needle 101 includes a cylindrical portion 102 of uniform wall thickness which is connected to a tapered portion 103 which is of increasing wall thickness towards the smaller portion and this portion 103 is connected to a portion 104 which is cylindrical and is of uniform wall thickness and this portion 104 is connected by a tapered portion 105 of uniform wall thickness which in turn is connected to a tapered portion 106. This portion 106 is of general cruciform shape which is shown in Fig. 9 and includes outer portions 107 joined by reversely curved arcuate portions 108.

20 This construction gives a very rigid, firm needle for a deep injection while at the same time the maximum periphery of the puncture is not increased so that in certain types of injection a very desirable effect is secured.

25 In Figs. 10 and 11 I show a modification of my invention wherein the needle indicated generally at 110 is mounted in the base 111 and the needle at one end includes a cylindrical portion of uniform wall thickness as at 112, a taper portion 113, and an end portion 114, both of which are of uniform thickness and the forward end of which is pointed as at 115. At the other end the needle includes a tapered portion 115' which is shown as sharpened so that it may be used to pierce an ampule cork or for other purposes.

30 The portion 115 is provided with a peripheral groove 116 in which the end wall 117 of a spring 118 is mounted. The forward end of the spring 118 has an annular member 119 secured thereon as by soldering. I show a rubber suction cup 119^a on the member 119. This cup 119^a serves to hold the needle in the desired locality and also serves to stretch the skin of the patient. In 35 operating after the suction cup is in place it is pierced by the needle as it advances into the patient. After each injection a new cup is placed on the member 119. In the use of the modified form of my needle the usual injection is made 40 and the spring member 118 acting in conjunction with the member 119 serves to limit the depth of the injection.

45 In Figs. 12 and 13 I show a modification of my invention wherein the needle 120 includes an end portion 121 which is fitted in a base 122. The portion 121 is cylindrical and of uniform wall thickness and is connected to a protuberant portion 123 the outer surface of which is rounded. The portion 122 is connected to a portion 124 which uniformly tapers forwardly to a location 50 124 whence the needle gradually assumes an oval position as shown in Figs. 13 and 14 at 125. At this point the needle is pointed as at 126 and is provided with peripheral grooves 127 which serve 55 as vents to allow surplus solution to escape from the injection puncture.

60 In Figs. 15 and 16 I show a modification of my invention wherein the needle includes a frusto-conical portion 130 which is connected to a cylindrical end portion 131. The frusto-conical portions merge into a forward portion 132 which is tapered but at less degree than the portion 130 while the portion 130 is continuous to an end portion 133 which is bevelled as at 134.

65 The needle shown in Fig. 17 is similar to that

shown in Fig. 16 except that the portions 130', 131', and 133' are all of uniform wall thickness and are provided with a forward pointed portion 134'.

70 The needle shown in Fig. 18 includes an end portion 140 which is fitted in a base 141. The forward end of the needle portion tapers at 142 to a portion of minimum diameter 143 whence the needle cross-section increases to a location 144 whence it again decreases at a point 145. The needle shown in Fig. 18 has a circular periphery and the inner portion is uniform throughout so that the needle wall varies. The location 144 may be advanced from the point 145 depending upon the purpose for which the 15 needle is to be used.

75 It will be understood that the needles embodying the features of my invention may be made of suitable material such as gold, platinum, stainless steel, or various alloys. The material 20 with which the needles are made may be worked cold to cause the material to harden or the needle may be heat treated. I now feel that it is preferable to have the small sharpened end hard and the larger end soft. In this case the 25 larger end should have more strength to prevent breakage due to the softer condition.

80 The strength of the larger end may be increased by an increase of metal or by increasing the diameter over that of the sharpened portion, that is, the larger end may have a greater section modulus than the sharpened portion or a greater moment of inertia by having a greater moment of inertia in the larger portion than at the sharpened portion. By making the sharpened portion harder and the larger portion of increased size a needle of greater strength may be provided yet the needle will have greater resistance to crystallization than a needle of uniform moment of inertia and uniform hardness. 35

85 It will be seen that with my invention the strength can be secured where desired and the wall thickness can be controlled so that the maximum of injection efficiency can be secured.

90 Having thus described my invention I claim: 45

1. A hypodermic needle including a plurality of stepped portions with the portion comprising the smallest step having a thicker wall than the other portions.

2. A hypodermic needle including a plurality of stepped portions with the portion comprising the smallest step having a thicker wall and being harder than the other portions.

3. The combination of a hypodermic needle having a groove therein and a depth regulating member including a coiled spring, said spring having a loop fitting said groove, said spring having a flesh engaging annular member thereon remote from the needle, said flesh engaging member directly engaging said spring. 55

4. In a hypodermic needle, the combination of a needle and an injection actuating device, said device including a spring engaging the needle, spring release means shiftable to release the needle and adjustable means on the needle and co-acting with said device to limit the depth of 60 the injection.

5. In a hypodermic needle, a base and a needle member, said needle member comprising an integral body including a cylindrical portion secured to said base, a bevelled portion on said cylindrical portion, said bevelled portion having its wall thickness increasing away from said cylindrical portion, a second cylindrical portion on said bevelled portion, a second bevelled portion 70

of uniform thickness on the end of said second cylindrical portion and a third cylindrical portion on the end of said last mentioned bevelled portion.

- 5 6. In a hypodermic needle, the combination of a needle and an injection actuating device, said needle having a pair of spaced engaging members therein and said device including a collar, said collar having a spring thereon, said spring at the 10 end remote from the collar including one coil engaging said needle adjacent to said engaging members, said collar having a pair of spaced arms thereon, said arms being adapted to fit between said engaging members, said arms having their 15 ends bevelled, said arms being movable to a position beneath said one coil whereby to cause one coil to expand to free the spring.
7. In a hypodermic needle, the combination of a needle and an injection actuating device, said 20 needle having a pair of spaced engaging members therein and said device including a collar, said collar having a spring fixed thereon, said spring in the end remote from the collar includ-

ing one coil engaging said engaging members, said collar having a pair of spaced arms thereon, said arms being adapted to fit between said engaging members, said arms having their ends bevelled, said arms being movable to a position beneath said one coil whereby to cause one coil to expand to free the spring and adjustable means on the needle to limit the movement of the arms to thereby limit the depth of the injection. 5

8. In a hypodermic needle, a base and a needle 10 member, said needle member comprising an integral body including a cylindrical portion secured to said base, a bevelled portion on said cylindrical portion, said bevelled portion having its wall thickness increasing away from said cylindrical portion, a second cylindrical portion on said bevelled portion, a second bevelled portion of uniform thickness on the end of said second cylindrical portion and a third cylindrical portion on the end of said last mentioned bevelled 15 20 portion.

GEORGE E. BARNHART.
